(57) **CLAIM**

The ornamental design for a tape measure, as shown and described.

DESCRIPTION

FIG. 1 is a perspective view of a tape measure showing a first embodiment of our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is bottom plan view thereof;

FIG. 7 is a top plan view thereof;

FIG. 8 is a perspective view of a tape measure showing a second embodiment of our new design;

FIG. 9 is a left side elevational view thereof;

FIG. 10 is a right side elevational view thereof;

FIG. 11 is a front elevational view thereof;

FIG. 12 is a rear elevational view;

FIG. 13 is a bottom plan view thereof; and,

FIG. 14 is a top plan view thereof.

The broken line showing is for illustrative purposes only and forms no part of the claimed design.

1 Claim, 8 Drawing Sheets

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 14.

UNITED STATES PATENT AND TRADEMARK OFFICE
CERTIFICATE OF CORRECTION

PATENT NO. : Des 441,309 S
DATED : May 1, 2001
INVENTOR(S) : Evans, Jr. et al.
